FILTER

Thomas Harold Slater, Fairview, Ill.

Application May 20, 1947, Serial No. 749,236

1 Claim. (Cl. 210—164)

1

This invention relates to a filter, and more particularly to a filter for use in the cooling system of an internal combustion engine.

The primary object of the invention is to exclude mud, silt, scale and the like from the small passages in the radiator of a cooling system, through which the cooling liquid is circulated.

Another object is to facilitate the rapid removal of the filter from the cooling system for cleansing, and to render the interior of the filter readily cleanable.

The above and other objects may be attained by employing this invention which embodies among its features a tubular body, end walls at opposite ends of the body, an outstanding tubular nipple on each end wall communicating with the interior of the body, a foraminous cylinder fixed at one end to an end wall of the body and extending toward the opposite end wall thereof in concentric spaced relation to the nipples, a cap closing the end of the foraminous cylinder in spaced relation to the end wall opposite that to which the cylinder is fixed, and a pipe entering the foraminous cylinder through the nipple carried by the wall to which the foraminous cylinder is fixed and terminating in spaced relation to the cap.

Other features include mounting the pipe to slide longitudinally into and out of the nipple so that it may be withdrawn to render the interior of the filter accessible for cleaning, and a flange extending outwardly from one end of the pipe to limit the distance that the pipe may enter the foraminous cylinder through the nipple.

In the drawings,

Figure 1 is a fragmentary side view of an internal combustion engine and radiator for the cooling system thereof illustrating this improved filter coupled in the system.

Figure 2 is an enlarged longitudinal sectional view through the filter, and

Figure 3 is a transverse sectional view taken substantially along the line 3—3 of Figure 2.

Referring to the drawings in detail, an engine block 10 is equipped with a conventional cooling fluid discharge coupling 11 to which a flexible hose 12 is coupled in a conventional manner. This hose 12 normally discharges into a nipple 13 carried at the upper end of a conventional radiator 14, so that the heated cooling fluid leaving the engine block 10 will be directed through the radiator 14, and cooled to be re-circulated through the engine block 10 in the conventional manner. The cooling fluid or liquid ordinarily contained in the cooling system frequently attacks the walls

5 of the passages through which it flows, causing them to rust and scale, and the minute particles are carried by the cooling liquid into the small passages of the radiator 14 with the result that these passages are likely to become clogged. Such clogging of the passages of a radiator seriously impairs its efficiency as a cooling device for the liquid, and at times serious damage to the engine may result.

10 In order to overcome these difficulties, I introduce into the system between the engine block 10 and the radiator 14 a filter, designated generally 15. This filter comprises a tubular body 16 spun at one end to form a dome-shaped end wall 17 and an outwardly extending tubular discharge nipple 18 which aligns axially with the axis of the tubular body 16. The end of the body 16 opposite the end wall 17 is closed by an end wall 19 carrying an annular retaining flange 20 which may be soldered or otherwise fixed to the tubular body 16. A tubular nipple 21 extends outwardly from the wall 19 in axial alignment with the nipple 18, and these nipples are of a diameter readily to fit within the flexible hose 12 commonly employed to couple the fitting 11 with the nipple 13 in the cooling system.

15 Soldered or otherwise fixed to the end wall 19 in spaced concentric relation to the nipple 21 and the tubular body 16 is a foraminous cylinder 22. 20 As illustrated in Figure 2, this cylinder extends from the inner face of the end wall 19 toward the end wall 17, but terminates short of the end wall 17 and is provided with a dome-shaped cap 23 forming an end closure for the foraminous cylinder. The cylinder 22 and the cap 23 form a filter 25 unit within the tubular body 16, and the interstices in the foraminous cylinder 22 are of such minute diameter as to prevent particles of scale or the like carried by the cooling liquid from passing through the foraminous cylinder.

25 Entering the foraminous cylinder 22 through the nipple 21 is a pipe 24, one end of which is provided with an out-turned annular flange 25. This pipe 24 is of a diameter snugly to fit the internal diameter of the nipple 21 so that even though the pipe may be extracted from the nipple, it will be held therein by frictional contact therewith. The pipe 24 is of a length sufficient so that when the flange 25 abuts the outer end of the nipple 21, the inner end of the pipe will be spaced from the dome 23 so that liquid entering the pipe 24 will be discharged from the inner end thereof into the interior of the foraminous cylinder 22 adjacent the end remote 55 from the wall 19.

In use, the hose length 12 which normally establishes communication between the fitting 11 and nipple 13 is severed and cut into shorter lengths 12 and 12a and the nipple 21 is entered into the hose length 12 and clamped thereon by a conventional hose clamp 26. The nipple 18 is then entered into the hose length 12a and clamped thereon by a conventional hose clamp 27. With the hose clamps 26 and 27 properly tightened, no leakage will occur around the junction of the hoses with the nipples. Assuming the cooling system to be filled with liquid, it will be obvious that when the engine is set into operation the cooling liquid will flow through the discharge coupling 11 and into the hose length 12 from whence it passes through the pipe 24 into the interior of the foraminous cylinder 22 which serves to arrest scale and like foreign matter. The liquid continues on through the perforations in the foraminous cylinder and is discharged through the nipple 18 into the hose length 12a from whence it enters the nipple 13 and radiator 14. In this way, any foreign matter carried from the engine block 10 toward the radiator will be arrested by the filter 15, and clogging of the small passages in the radiator will be avoided. The foreign matter will collect within the filter between the foraminous cylinder 22 and the pipe 24, and periodically the filter may be removed from the cooling system and the pipe 24 extracted, thus giving access to the material collected with the filter which may be flushed out, as by coupling the nipple 18 to a source of water pressure and allowing the liquid to flow through the filter in a reverse direction. Once having been cleaned, the pipe 24 may be re-introduced into the foraminous cylinder 22 through the nipple 21 and the flange 25 will serve properly to space the inner end of the pipe from the cap 23.

While in the foregoing there has been shown

and described the preferred embodiment of this invention, it is to be understood that minor changes in the details of construction, combination and arrangement of parts may be resorted to without departing from the spirit and scope of the invention as claimed.

Having described the invention, what is claimed as new is:

10 A filter adapted to be introduced in the cooling system of a liquid cooled internal combustion engine between the cooling liquid discharge of the engine block and the radiator, comprising a tubular body, end walls at opposite ends of the body, an outstanding tubular nipple on each end wall communicating with the interior of the body, a foraminous cylinder fixed at one end to an end wall of the body and extending toward the opposite end wall thereof in concentric spaced relation to the nipples, a cap closing the end of the 20 foraminous cylinder in spaced relation to the end wall opposite that to which the cylinder is fixed, a pipe slidably fitted into the nipple carried by the end wall to which the foraminous cylinder is fixed, said pipe being adapted to project into the 25 foraminous cylinder and an outstanding annular flange on the pipe for engaging the end of the said nipple and limiting the distance that the pipe may enter the cylinder.
